PROCESS OF AND MACHINE FOR MAKING
BOOK MATCHESWilly Lück, Stuttgart, Germany, assignor to
Pullimatch Incorporated, New York, N. Y., a
corporation of DelawareApplication June 29, 1936, Serial No. 87,821
In Germany September 21, 1934

11 Claims.

(CL 93-2)

The invention relates to the manufacture of book matches, that is to say small packets consisting of doubled sheets of cardboard or the like, with corrugated strips attached to their inside faces and matches in the pockets formed by the corrugations. Generally there are coatings of frictional ignition coating inside the pockets, so that the matches are ignited by the act of withdrawing them.

10 The usual method of making such book matches consists in first joining to each other a long cover strip and a long composite strip holding the matches, and then cutting the united strips transversely into sections of such length as 15 is required to produce the separate books, the sections being then folded.

According to my invention the composite strip holding the matches is divided into sections before the transverse cutting of the united strips, and the sections of match strip are joined to the cover strip with gaps between them, the subsequent folding being performed in these gaps, so that only the cover strip is bent by the folding operation.

25 The match strip may before the final cutting of the united strip be cut into sections each of which comprises the matches for one side of a book, but a more simple method consists in arranging that each match strip section comprises 30 enough matches for two sides of a book, but that this group of matches is cut in half by the final cutting operation, one half belonging to one book, and the other half to another book.

An embodiment of the invention is illustrated 35 in the accompanying drawing, in which

Fig. 1 is a front view of the machine, with omission of parts not essential to understanding the invention,

Fig. 2 a side view, and

Fig. 3 a plan view of a detail of the machine.

40 A driving shaft 1 having a drum 2 fixed thereto is mounted in a frame 3. The shaft also has fixed thereto a gear wheel 4 and a disk 5 with a series of tappets 5¹ on its rim. On a pivot 6 fixed 45 to the frame there is mounted a forked arm 7 carrying the axle 8 of a second drum 9, and the axle 8 has fixed thereto a gear wheel 10 adapted to mesh with the gear wheel 4. A nose 11 projecting from the arm 7 rests on the disk 5, and 50 in the course of rotation of the disk the tappets 5¹ lift the arm so that at intervals the wheel 10 is disengaged from the wheel 4. On a tail of the arm 7 there is a screw 12 engaging a slide 13 carrying a plurality of knives 14 on a wheel 15, 55 the purpose of the screw being to adjust the

knives in relation to the drum 9. The wheel 15 is fixed to gear wheel not shown in the drawing, this gear wheel being in engagement with the wheel 10.

A composite strip 16 is fed over a roller 17 to the drum 9, and consists of a smooth strip *a* of cardboard having a corrugated strip *b* of cardboard glued thereto, matches *c* being carried in the pockets formed by the corrugations. The corrugations are disposed in groups of five, with 5 flat portions *b*¹ of some width between the groups. The roller 17 applies glue to the exposed side of the strip *a*.

A cover strip 18 of cardboard is fed to the drum 2 and meets the glue coated face of the strip 16 15 in the gap between the two drums, the drums applying light pressure sufficient to unite the two strips.

Before the strip 16 is united with the strip 18 it is cut into sections *d* (Fig. 3) by the knives 14, 20 each section comprising two groups of corrugations. Owing to the action of the tappet wheel 5, 5¹ the feed of the strip 16 is interrupted at intervals, so that gaps *e* occur between the sections of match strip placed on the cover strip 25 18, the cut pieces of strip 16 being guided to the nip of drum 2 and drum 9 by a guide member 17¹.

The united strips are fed by the drums to a table 19 having above it a guillotine knife 20, which descends at intervals so as to cut the strip 30 transversely, as indicated by the line 20¹ in Fig. 3. The front portion of strip on the table 19 lies over the mouth of a chute 21 and under a vertically reciprocating flat plunger 22, which descends when the knife 20 has made a cut and 35 pushes the severed portion of the strip into the chute, thereby folding it into book form. At the bottom of the chute there is a conveyor for carrying the books away. The fold is made in the gap *e* so that only the cover strip is bent by the 40 folding device.

The drum 9 may have a ring of teeth adapted to engage the corrugations of the strip *b*. Additional appliances for various purposes may be incorporated in the machine, for example a printing device for printing inscriptions on the cover or inside the book.

What I claim as my invention and desire to secure by Letters Patent of the United States is:—

1. The process of producing book packages of 50 matches which consists in attaching to a cover strip a series of match strip sections spaced apart by a gap, dividing the combined strips into lengths by means of transverse cuts made 55 through the centres of the match strip sections,

and folding each severed length of the combined strips at the gap between the two portions of match strip thereon.

2. The process of producing book packages of matches which consists in attaching to a cover strip a series of match strip sections spaced apart by a gap, each of said match strip sections comprising two groups of matches and a connecting portion between them, dividing the combined strips into lengths by means of transverse cuts made in the connecting portions between the two groups of matches of each match strip length, and folding each section of the combined strip at the gap between the two portions of match strip sections thereon.

3. The process of producing book packages of matches which consists in imparting continuous feed movement to a cover strip, intermittently feeding to said cover strip a series of adhesive coated sections of match strip, whereby said match strip sections are serially attached to said cover strip with gaps between the sections, dividing the combined strips into lengths by means of transverse cuts made through the centers of the match strip sections, and folding each severed length of the combined strips at the gap between the two portions of match strip thereon.

4. The process of producing book packages of matches which consists in imparting continuous feed movement to a cover strip, intermittently feeding to said cover strip a series of adhesive coated sections of match strip, whereby said match strip sections are serially attached to said cover strip with gaps between the sections, each of said match strip sections comprising two groups of matches and a connecting portion between them, dividing the combined strips into lengths by means of transverse cuts made at the connecting portions between the two groups of matches of each match strip section, and folding each length of the combined strip at the gap between the two portions of match strip sections thereon.

5. In a machine for making book packages of matches the combination of a continuously driven feed drum for a cover strip, a feed drum arranged to feed an adhesive coated match strip having pockets therein and matches in said pockets into contact with said cover strip, means for automatically severing said match strip at regular intervals at a part which has not reached said cover strip, means for intermittently driving said second mentioned feed drum so that the sections into which said match strip is cut by the severing operation are attached to said cover strip with gaps between them.

6. In a machine for making book packages of matches the combination of a continuously driven feed drum for a cover strip, a feed drum arranged to feed an adhesive coated match strip having pockets therein and matches in said pocket-

ets into contact with said cover strip, means for automatically severing said match strip at regular intervals at a part which has not reached said cover strip, two gear wheels fixed to said feed drums respectively, adapted to mesh for driving said second mentioned drum, and means for disengaging said gear wheels from each other at regular intervals by movement of said second mentioned drum, so that the sections into which said match strip is cut by the severing operation are applied to said cover strip with gaps between them.

7. In a machine for making book packages of matches the combination claimed in claim 6, the means for disengaging said gear wheels comprising a pivoted arm carrying said second mentioned drum and a cam acting upon said arm.

8. In a machine for making book packages of matches the combination claimed in claim 6, the means for disengaging said gear wheels comprising a pivoted arm carrying said second mentioned drum and a cam acting upon said arm, said arm carrying said automatic means for severing said match strip, and said severing means comprising a knife wheel and a gear wheel fixed thereto in mesh with the gear wheel fixed to said second mentioned drum.

9. In a machine for making book packages of matches the combination of means for attaching to a cover strip a series of match strip sections spaced apart by a gap, means for producing transverse cuts through the centers of the match strip sections to divide the combined strips into lengths, and means for folding each severed length of the combined strips at the gap between the two portions of match strip thereon.

10. In a machine for making book packages of matches the combination of means for continuously feeding a cover strip, means for intermittently feeding a series of adhesively coated sections of match strip into attaching relationship with said cover strip, whereby said match strip sections are serially attached to said cover strip with gaps between the sections, means for producing transverse cuts through the centers of the match strip sections to divide the combined strips into lengths, and means for folding each severed length of the combined strips at the gap between the two portions of match strip thereon.

11. The process of producing book matches which comprises feeding a continuous match strip, cutting the match strip into separate pieces, intermittently feeding and attaching the separate pieces of match strip to a cover in spaced apart relationship, and folding the cover between said pieces of match strip in such direction that said pieces of match strip are attached respectively to the inside of said cover at opposite sides of the fold.

CERTIFICATE OF CORRECTION.

Patent No. 2,093,613.

September 21, 1937.

WILLY LUCK.

It is hereby certified that error appears in the printed specification of the above numbered patent requiring correction as follows: Page 1, second column, line 7, for "coardboard" read cardboard; page 2, first column, line 12, claim 2, for "length" read section; and line 13, same claim, for "section" read length; and that the said Letters Patent should be read with these corrections therein that the same may conform to the record of the case in the Patent Office.

Signed and sealed this 16th day of November, A. D. 1937.
